DESIGN FOR A HANDKERCHIEF OR SIMILAR ARTICLE

Winifred S. Mogabgab, New York, N. Y.

Application April 8, 1944, Serial No. 113,179

Term of patent 14 years

(Cl. D3—12)

To all whom it may concern:

Be it known that I, Winifred S. Mogabgab, a citizen of the United States of America and a resident of the city, county, and State of New York, have invented a new, original, and ornamental Design for Handkerchiefs or Similar Articles, of which the following is a specification, reference being had to the accompanying drawing, forming a part thereof.

In the drawing:

Fig. 1 is a plan view of one corner of a handkerchief disclosing my new design; and

Fig. 2 is a view in side elevation of the design viewing the same from the left side of the Fig. 1.

The other three corners of the handkerchief are unornamented.

I claim:

The ornamental design for a handkerchief or similar article, substantially as shown and described.

WINIFRED S. MOGABGAB.
